UNITED STATES PATENT OFFICE.

HENRY B. MALDEIS, OF BALTIMORE, MARYLAND.

MANUFACTURE OF HORSE-COLLARS.

SPECIFICATION forming part of Letters Patent No. 393,166, dated November 20, 1888.

Application filed August 18, 1888. Serial No. 283,143. (No model.)

To all whom it may concern:

Be it known that I, HENRY B. MALDEIS, a citizen of the United States, residing at Baltimore, in the State of Maryland, have invented 5 certain new and useful Improvements in the Process of Making Horse-Collars, of which the following is a specification.

This invention relates to an improved method of making horse-collars of the "Kay" style. 10 In the drawings herewith, Figure 1 is a cross-section of the collar on the line 1 1 of Fig. 3. Fig. 2 is a view of part of a collar, showing some details. Fig. 3 is a face view of the collar, being that side which comes in contact with 15 the animal.

The letter A designates the body of the collar; B, the rim; c, the facing; and D, the stuffing, of felt or hair, which fills the crease between the body and rim. To make this style of collar so that the crease-stuffing D will fill the 20 crease-cavity between the body A and rim B, and serve as a pad and impart softness to the facing, is the desideratum, and I effect this object by first sewing up all the seams which 25 unite the body and rim parts, stuffing the rim-cover, partly filling or stuffing the body, laying the felt or hair in the crease-cavity, stretching the loose facing over the crease-stuffing and securing it, and finally finish stuffing the partly-filled body. The facing c, face-lining c', and 30 back d are first united by a seam, e. Then the rim-cover f, the said back d, face-lining c', and the housing g, interposed between the rim-cover and back, are united by a seam, h. These two seams e h form and unite the body 35 and rim parts ready for stuffing, but leaves one edge, c'', of the facing loose or unattached, and also likewise leaves one edge, g', of the housing loose. The rim-cover f is then stuffed or filled 40 with material to form the rim B. The body A is then partly formed by about half filling

between the face-lining c' and back d with straw or other stuffing material. Hair or felt D, in suitable quantity to fill the crease in front of the seam h and act on the facing c, so as to 45 form a pad, is then laid or placed in position. The loose facing c is then drawn from the seam e over and covers the crease-stuffing D and partly around the rim B, to which its edge c'' is secured by tacks i; or stitches may be used 50 instead. The loose edge g' of the housing covers the row of tacks, and is then laced to the facing by stitches j. Finally, the remainder of the stuffing is put in the partly-filled body, and when full the effect will be to draw the facing 55 c tightly over the crease-stuffing. By this procedure the crease-cavity can be well filled, and at the same time the said filling will serve as a pad and impart softness to the facing.

The method which includes, first, partly filling the body A, placing the stuffing along the crease, and afterward finish filling the body may obviously be employed without reference to the housing g. This latter may therefore be used or omitted. 60

Having described my invention, I claim—

The method of making horse-collars, consisting of, first, sewing the seams which form and unite the body and rim parts, then stuffing the rim, partly filling or stuffing the body, placing 70 stuffing material D in position along the crease between the rim and body, covering it with the facing c, and securing the edge of said facing to the rim by suitable fastenings, and finally finish stuffing the partly-filled body, as set 75 forth.

In testimony whereof I affix my signature in the presence of two witnesses.

HENRY B. MALDEIS.
